To all whom it may concern:

Be it known that I, COLEMAN LOWELL FOWLER, a citizen of the United States, residing at Chicago, county of Cook, and State of Illinois, have invented and produced a new and original Design for Gravity-Pawls, of which the following is a specification, reference being had to the accompanying drawings, forming a part thereof.

Figure 1 is a plan view of a pawl showing my new design. Fig. 2 is a second view taken on the line 2-2 of Fig. 1, as shown in the drawings.

The leading or material feature of my design consists of a flat rectangular plate provided with a central opening B, having the

recess C, provided with one abrupt and with one rounded shoulder, the recess C being positioned at a slight angle to the line of the plate.

Having described my invention, what I claim as new, and desire to secure by Letters Patent, is—
